[57] CLAIM

The ornamental design for a fabric gift bag with gift booklet and receptacle therefor, as shown and described.

DESCRIPTION

FIG. 1 is a front elevational view of a fabric gift bag with gift booklet and receptacle therefor showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear perspective view thereof with gift booklet shown in a lower closer position to the gift booklet receptacle; and,

FIG. 8 is a rear perspective view thereof with gift booklet shown in a lower closer position to the gift booklet receptacle and tie shown in dashed lines around the compressed neck of the gift bag.

The broken lines shown in FIG. 4 are representative of standard stitching. The broken line showing of a tie in FIG. 8 is for illustrative purposes only and forms no part of the claimed design.
